COMBINATION AIRCRAFT COWLING AND FUEL
TANK WRENCH

John G. Glenn, Ontario, and Jack B. Jones, Upland, Calif.

Application September 13, 1954, Serial No. 32,251

Term of patent 7 years

(Cl. D54—16)

FIG. 1.

FIG. 2.

FIG. 3

FIG. 4.

Fig. 1 is a perspective view of a combination aircraft cowling and fuel tank wrench showing our new design;
Fig. 2 is a front elevational view;
Fig. 3 is a rear elevational view; and
Fig. 4 is a bottom plan view thereof.

We claim:

The ornamental design for a combination aircraft cowling and fuel tank wrench, as shown.
